UNITED STATES PATENT OFFICE.

JAFEW S. VAN BUREN, OF ALBANY, NEW YORK.

DESIGN FOR A PANEL FOR DOORS FOR STOVES OR RANGES.

SPECIFICATION forming part of Design No. 32,644, dated May 8, 1900.

Application filed April 10, 1900. Serial No. 12,379. Term of patent 7 years.

To all whom it may concern.

Be it known that I, JAFEW S. VAN BUREN, a citizen of the United States, residing at Albany, in the county of Albany and State of New York, have invented and produced a new and original Design for a Panel for Doors for Stoves or Ranges, of which the following is a specification, reference being had to the accompanying drawing, forming a part thereof.

The figure is an elevation of a panel, showing my new design.

As shown in the drawing, in the center of the panel is a depressed corrugated surface A, surrounded by a border B. This border B at C C' consists of a series of short ribs and

at D D' is made up of scrollwork d' d' and a series of larger ribs d.

Having fully described my invention, what I claim as new, and desire to secure by Letters Patent, is—

The design for a panel for a door for a stove or range as herein shown and described.

In testimony whereof I have signed my name to this specification in the presence of two subscribing witnesses.

JAFEW S. VAN BUREN.
